SPOONS.

UNITED STATES PATENT OFFICE
PATRICK CONCANNON, OF WALLINGFORD, CONNECTICUT,
DEVICE FOR PLATING SPOONS.
Patent No. 225,571, dated March 10, 1880.
11 shafts,

OF WALLING,
OR PLATING SPOONS.
of Letters Patent No. 225,571, dated March 16, 1880.
Application filed February 10, 1880.

The letter A represents the dipping or bath tank, wherein is placed the solution into which the spoons are dipped. It is provided with the forked thumb-screws a , which project vertically from the frame A, wherein may be rigidly secured female screws for their reception. The holder-frame A' is provided with the metal arms m , which are secured thereon and have their bearings in the screws a . This arrangement will elevate or lower the spoons.

The holder-frame A' is provided with horizontal arms m m, which are secured thereto. These arms have their bearings in the fork of the thumb-screws a a. This arrangement enables the operator to elevate the frame A', and thus adjust it to the lower position in which the spoons are to be partially dipped, the parts thereof most exposed to being replated after the articles are finished.
